UNITED STATES PATENT OFFICE.

IR A. W. NONNEMAN, OF WARREN, OHIO, ASSIGNOR TO THE BORDEN COMPANY, OF WARREN, OHIO, A CORPORATION OF OHIO.

DIE-STOCK.

1,292,025.

Specification of Letters Patent.

Patented Jan. 21, 1919.

Application filed November 3, 1917. Serial No. 200,010.

To all whom it may concern:

Be it known that I, IR A. W. NONNEMAN, a citizen of the United States, residing at Warren, in the county of Trumbull and State of Ohio, have invented a certain new and useful Improvement in Die-Stocks, of which the following is a full, clear, and exact description, reference being had to the accompanying drawings.

10 This invention relates to die stocks of the type wherein the cutting chasers occupy fixed positions in operation, but are adjustable for different sizes of pipe to be cut. A suitable guiding device is provided, also 15 adjustable for different sizes of pipe. The invention is concerned with means for adjusting the chasers and guides for the different sizes and for locking them in adjusted position, the object being to provide such 20 characteristics in a form which shall be simple, positive and easily operable. The invention is hereinafter more fully described and its essential characteristics set out in the claims.

25 In the drawings, Figure 1 is a plan of a die stock embodying my invention; Fig. 2 is a central cross section of the same as indicated by the line 2—2 on Fig. 1; Fig. 3 is a perspective of the frame member which 30 carries the chasers and guides; Fig. 4 is a cross section as indicated by the line 4—4 on Fig. 1; Figs. 5 and 6 are sectional views on planes parallel with Fig. 1 looking in opposite directions to show the scrolls for operating the guides and chasers respectively, the planes of these views being indicated by the lines 5—5 and 6—6 on Fig. 4; Figs. 7 and 8 are perspectives of one of the chasers and one 35 of the guide blocks employed in the embodiment shown.

40 What may be called the frame of my die stock consists of a rotatable member preferably of the form shown in Fig. 3, having radial recesses for the chasers and guides. This 45 member is designated 10. It is preferably a single integral casting, but may be described as made up of the following parts, namely: An inner sleeve portion 11 slightly larger than the external diameter of the 50 largest pipe to be cut, an outer wall or sleeve 12 concentric with the sleeve 11, an annular transverse web 13 connecting the inner and outer wall, and webs 14 arranged in pairs, each parallel with, and on opposite sides of

a radius of the structure and extending between the inner and outer wall. Beside the parts mentioned are two tubular extensions 15 on diametrically opposite sides of the structure, for a purpose hereinafter explained.

55 The chasers extend radially and are mounted in the housing provided by the webs 14 and the annular web 13. These chasers are designated 20 and may have the usual cutting teeth on their inner edges. 60 They are also shown as provided with lugs 21 adapted to engage in grooves in a scroll plate, the rotation of which shifts the chasers in or out.

65 The scroll plate for the chasers is designated 30. It has a central opening adapted to seat over the projecting portion of the inner cylindrical wall 11 and has scroll or cam grooves 31 adapted to receive the lugs 21 of the chasers. This scroll plate is stiffened on its outer side by an annular reinforcing web 33 and inclined radial webs 34. 70 The scroll plate being journaled on the central sleeve 11, it follows that the rotation of the plate around such sleeve will move the 75 chasers in or out.

75 To make the chasers readily removable to allow other chasers to be substituted, I form outwardly extending radial portions 35 of the grooves 31. These portions extend to the 80 extreme outer edge of the plate, and, when they are opposite the lugs 21, the chasers may be readily slid radially outward, out of the die stock.

85 The guide for the pipe consists of a plurality of bars 40 arranged radially about the axis of the pipe and adjustable in and out by a rotatable cam plate 50. This cam plate has a central opening by which it is journaled on the extension 17 of the inner sleeve 11. 90 The plate is shown as provided with cam ribs 52 and 53 which engage in notches 44 in the guides 40. Each cam rib 52 or 53 extends substantially half way about the cam plate and the radial distance between the innermost portion of one rib and the outermost portion of the other rib substantially equal with the distance between the notches in a 95 guide bar.

100 It results from the above construction that if the cam plate 50 be rotated about its axis, the ribs serve to force the blocks 40 in or out radially. Furthermore, if the plate

makes more than a half rotation, as the rib which was moving the block leaves one notch, the other rib comes into the other notch and continues the driving. Thus a 5 movement of this cam plate nearly a complete rotation is allowed to cause an easy and gradual movement of the guide blocks. Suitable lugs 58 on the cam plate enable it to be readily turned.

10 To clamp the cam plates 30 and 50 and effectively lock them in any set position I provide devices now to be described.

Extending integrally from the frame 10 on diametrically opposite sides are the tubular members 15 heretofore mentioned. 15 These members are internally threaded at 18 for the reception of removable handles 60 by which the die stock is operated. The exterior of these sleeves is smooth and cylindrical for a short distance adjacent to the sleeve 12 as shown at 19. On these smooth cylindrical portions are mounted slideable clamps 70 and 71 adapted to engage and lock the cam plates. These clamps are forced toward the cam plates by hand nuts 73 and 74 having a screw threaded interior which screws on the threads 19^a on the exterior of the extensions 15.

It will be seen from Fig. 2 that the edges 30 of the cam plates 30 and 50 are beveled as indicated at 36 and 56 respectively, and that the clamp 70 has two jaws 75 and 76 correspondingly beveled on their inner sides to lie against and clamp the two cam plates 30 and 50. Accordingly, the tightening of the nut 73 clamps both these plates. The clamp 71 has an inwardly beveled jaw 77 adapted to engage the bevel of the cam ring 30, while on the other end the jaw 78 of this cam plate 40 has its inner surface parallel with the top of the cam ring and loosely overhanging it. The body of this clamping plate 71 is provided with suitable abutment pins 79 adapted to engage the wall of the frame and prevent the clamping plate being forced askew. 45

It results from the above construction that the clamping plate 71, by the tightening of the nut 74, may clamp the cam plate 30 but will leave the cam plate 50 free, while the 50 clamp 70 tightening the screw 73, clamps both cam plates. In setting the die stock, both nuts 73 and 74 are loosened by hand, leaving both cam plates free; then the cam 30 is turned by hand until the chasers are 55 set in the desired position, whereupon the nut 74 is tightened and the clamp 71 holds this cam plate 50 without binding the cam plate 50. Then the die stock in this position 60 is put on the pipe and the guide blocks are adjusted into working engagement with the pipe by turning the cam plate 50, and, when adjusted, these guide blocks are locked by the tightening of the screw 73 which forces the clamping plate 70 inward and binds the 65 cam plate 50 to the frame. At the same time

the jaw 75 of this clamping plate further binds the cam plate 30 at that side of the frame and effectively locks the whole die stock.

The arrangement of two clamps, one acting on both cam plates and the other on only one, enables the ready setting and locking of the chasers in an accurate position according to the thread to be cut, and the subsequent locking of the guides in the position 75 determined by the actual exterior of the particular pipe being cut. By using the latter lock to clamp the chaser plate also at that side, I hold it most effectively and rigidly. The construction, it will be seen is 80 extremely simple; there is nothing about it to get out of order, and at the same time it is very effective in enabling ready changes in the setting of the die stock and the locking in different set positions. 85

By mounting the clamping devices on the extensions 15 provided for the operating handles no extra members are required and all parts of the clamps are out of the way. The clamps also serve the purpose of holding the die stock parts together, and no bolts or screws are required for this purpose. The simple loosening of the hand nuts until the clamps are entirely withdrawn enables each cam plate to be removed, which enables the 95 removal of the guide blocks, as well as the chasers. This provides for ready cleaning of the die stock whenever desired. Ordinary interchange of chasers for different threads is effected without separating the 100 die stock by means of the extensions 35 of the scroll grooves, when the position of the cam plate 30 allows this operation. Normally the clamp holds this cam plate so that the chasers are retained in the die stock. 105 Oiling of the chasers in use, may be conveniently provided by means of a partition 80, between the inner and outer sleeves of the frame, which carries a radial oiling passage way 81. 110

Having thus described my invention, what I claim is:

1. In a die stock, the combination of a frame, chasers and guide bars carried thereby, cam plates on the opposite sides of the 115 frame for moving the chasers and guide bars respectively, a bodily movable clamp having rigid jaws adapted to overhang both cam plates, and means for moving said clamp as a unit.

2. In a die stock, the combination of a frame, chasers and guide bars carried thereby, a pair of cam plates on opposite sides of the frame for moving the chasers and guide bars respectively, a lateral extension from 125 the side wall of the frame, a clamp slideable on said extension and adapted to overhang both cam plates, and a nut screwing onto said extension for operating the clamp.

3. In a die stock, the combination of a 130

- frame, a set of radial chasers and a set of radial guide bars independently mounted in said frame, a pair of cam plates one for operating the chasers and the other for operating the guide bars, a slidable clamp having rigid jaws overhanging both cam plates, and means for forcing the clamp into engagement with both cam plates.
4. In a die stock, the combination of a frame, a set of chasers carried thereby, a set of guide blocks carried thereby, a pair of cam plates for operating the chasers and guide blocks respectively, each cam plate having a beveled edge, an extension on the frame, a clamp mounted on the extension and having a pair of beveled jaws overhanging the cam plates, and a nut mounted on the extension and adapted to bear against the clamping plate.
- 10 5. In a die stock, the combination of a frame, chasers and guide bars slidably mounted therein, a pair of cam plates on opposite sides of the frame for moving the chasers and guide bars respectively, a pair 15 of handle extensions projecting from opposite sides of the frame, clamps for the cam plates slidably mounted on said handle extensions, and nuts screwing onto the exterior of the handle extensions for operating the 20 slideable clamps.
6. In a die stock, the combination of a frame, a set of chasers mounted therein, a set of guide blocks mounted therein, a pair of cam plates for operating the chasers and 25 guide blocks respectively, each cam plate having a beveled edge, a movable clamp having a pair of inwardly beveled jaws adapted to overhang and engage both cam plates, a second clamp having one inwardly beveled 30 jaw which overhangs the chaser operating cam plate and is adapted to clamp it without clamping the guide bar cam plate, and means for operating the two clamps.
7. In a die stock, the combination of a frame, a set of chasers mounted therein, a set of guide blocks mounted therein, a pair of cam plates for operating the chasers and guide blocks respectively, a pair of extensions for the frame on diametrically opposite 40 sides, a pair of clamps slidably mounted on the extensions for locking the cam plates and a pair of operating nuts mounted on the extensions and bearing against the respective clamps.
- 55 8. In a die stock, the combination of a frame, a set of chasers mounted therein, a set of guide blocks mounted therein, a pair of cam plates for operating the chasers and guide blocks respectively, a pair of extensions for the frame in diametrically opposite sides and adapted to carry the operating handles, a pair of clamps loosely slidable on the extensions, one of said clamps adapted to engage both cam plates and the other 60 clamp only one cam plate, and a pair of operating nuts mounted on the extensions and bearing against the respective clamps.
- erating nuts mounted on the extensions and bearing against the respective clamps.
9. In a die stock, the combination of a frame, a set of chasers mounted therein, a set of guide blocks mounted therein, a pair of cam plates for operating the chasers and guide blocks respectively, each cam plate having a beveled edge, a movable clamp having a pair of inwardly beveled jaws adapted to overhang and engage both cam plates, a second clamp having one inwardly beveled jaw which overhangs the chaser operating cam plate and is adapted to clamp it without clamping the guide bar cam plate, and means for operating the two clamps.
10. In a die stock, the combination of a frame, a set of chasers mounted therein, a set of guide blocks mounted therein, a pair of cam plates for operating the chasers and guide blocks respectively of the frame, each cam plate having a beveled edge, a pair of tubular extensions adapted to carry the operating handles, a clamp movably mounted on one of said extensions and having a pair of inwardly beveled jaws adapted to overhang and engage both cam plates, a second clamp movably mounted on the other extension having one inwardly beveled jaw which overhangs the chaser operating cam plate and is adapted to clamp it without clamping the guide bar cam plate, and a pair of hand nuts threaded on the exterior of the handle extensions for operating the respective clamps.
11. In a die stock, the combination of a frame comprising an inner and an outer sleeve and a connecting web between them, radial chasers mounted in openings in the frame on one side of said connecting web, radial guide blocks mounted in openings in the frame on the other side of said connecting web, cam plates on the opposite sides of the frame coacting with the chasers and guide bars respectively, tubular extensions from the sides of the frame at diametrically opposite points, said extensions being provided on the interior with means for carrying the operating handles, a pair of clamps for the cam plates each movable as a unit, and nuts on the exterior of the extensions, for operating the clamps respectively.
12. In a die stock, the combination of a frame comprising inner and outer concentric sleeves and connecting members, a set of radial chasers mounted in openings in such frame, a set of radial guide blocks mounted in openings in such frame, a pair of rotative cam plates on opposite sides of the frame, journaled on cylindrical extensions of the inner sleeve, each cam plate carrying a scrolled shoulder coacting with a shoulder on the respective radially movable member, and a clamp having a rigid boss overhanging the two cam plates for

clamping the cam plates in position and for preventing their separation from the frame when unclamped.

13. In a die stock, the combination of a frame comprising inner and outer concentric sleeves and connecting members, a set of radial chasers mounted in openings in such frame, a set of radial guide blocks mounted in openings in such frame, a pair of rotative cam plates on opposite sides of the frame, each cam plate carrying a scrolled shoulder coacting with a shoulder on the re-

spective radially movable member, a pair of clamps located at the sides of the frame and having jaws overhanging the two cam plates, the jaws of one clamp being adapted to act on both cam plates and only one jaw of the other plate being active, and a pair of hand nuts for forcing the respective clamps toward the frame. 15

20 In testimony whereof, I hereunto affix my signature.

IRA W. NONNEMAN.
